N. C. COVINGTON & J. ALLRED.

SUPPORT.

APPLICATION FILED OCT. 1, 1915.

1,173,143.

Patented Feb. 22, 1916.

UNITED STATES PATENT OFFICE.

NORRIS C. COVINGTON AND JOHN ALLRED, OF ROCKINGHAM, NORTH CAROLINA;
SAID ALLRED ASSIGNOR TO SAID COVINGTON.

SUPPORT.

1,173,143.

Specification of Letters Patent. Patented Feb. 22, 1916.

Application filed October 1, 1915. Serial No. 53,489.

To all whom it may concern:

Be it known that we, NORRIS C. COVINGTON and JOHN ALLRED, citizens of the United States, residing at Rockingham, in the 5 county of Richmond and State of North Carolina, have invented certain new and useful Improvements in Supports, of which the following is a specification.

The supporting device which is the subject matter of the present application for 10 patent is designed for attachment to the outside of a building for the purpose of holding bedding in order that the same may be sunned and aired in the open air.

15 The invention has for its object to provide a device of the kind stated which is simple in construction, and easily put up or taken down, and which will securely hold the articles to be supported.

20 The invention also has for its object to provide a supporting device which can be folded out of the way when not in use.

With the objects stated in view, the invention consists in a novel combination and arrangement of parts to be hereinafter described and claimed, and in order that the 25 same may be better understood, reference is had to the accompanying drawing, in which—

30 Figure 1 is a plan view of the device; Fig. 2 is a side elevation thereof; Fig. 3 is a section on the line 3—3 of Fig. 1, and Fig. 4 is a detail in perspective.

In carrying out the invention there are 35 provided two brackets, each comprising a horizontal arm 5 having at its inner end a downward bend 6. The outer end of the bracket arm has an oblique rearward and downward bend 7 terminating at its lower 40 end in a straight downward bend 8 which is flattened, and has a forward bend 9 at the bottom to form a hook. The lower portion of the bend 8 is reduced in width, as indicated at 10. The parts 6 and 8 are vertically 45 spaced and in alinement, and they form pivots on which the bracket may be swung.

On the wall 11 of the building are mounted vertically spaced eye-bolts 12 and 13 which serve as bearings for supporting 50 the brackets. The pivot 6 seats in the upper eye-bolt 12, and the pivot 8 seats in the lower eye-bolt 13, the latter having a non-circular aperture conforming to the cross-sectional shape of the part 8. Before the bracket can 55 be swung, it is necessary to elevate the same

until the reduced part 10 of the part 8 enters the aperture of the eye-bolt 13, whereupon the bracket may be swung sidewise against the wall 11, out of the way. When the enlarged upper portion of the part 8 seats in 60 the aperture of the eye-bolt 13, the bracket cannot swing, and it is securely held projecting straight out from the wall 11. The hook 9 extends beneath the eye-bolt 13 and prevents the bracket from slipping up to 65 disengage the pivots from the eye-bolts.

The top of the eye-bolt 13 has a recess 14 extending transversely, and the reduced portion 10 of the part 8 forms a shoulder 15. When the bracket is swung sidewise against 70 the wall 11, the shoulder 15 enters the recess 14, whereby the bracket is locked in folded position, and before it can be swung out, it must be lifted sufficiently to take the shoulder out of the recess.

75 The two bracket members hereinbefore described are mounted in laterally spaced relation below and adjacent to a window 16 so that the part to be supported outside the latter may be readily put on or taken off. 80 As stated, the device is designed primarily for sunning and airing bedding in the open air.

The following means are provided for 85 holding the bedding on the bracket members: On the bracket arms 5 is placed an open-work shelf 17 composed of wire, and consisting of two hingedly connected sections, so that the shelf may be folded together and passed through the window 16 90 from the inside. Each shelf section is composed of marginal wires, and longitudinal and cross wires 18 and 19, respectively, the cross wires 19 having eyes 20 at their inner ends to receive a hinge rod 21, whereby 95 the hinge connection between the sections is had.

The shelf is placed on the bracket arms 5, and the bedding is placed on the shelf. On the longitudinal marginal wire of the 100 shelf section which is next to the window 16 are mounted spring clips 22 which engage the bracket arms to hold the shelf in place thereon.

The bedding is held down in place on the 105 shelf 17, and prevented from blowing off the same, by two holders, each comprising a rod 23 having depending hooks 24 and 25, respectively, at its ends. The outer end of the bracket arm 5 has an upstanding loop 110

or eye 26 to receive the hook 24, and the hook 25 is engaged under the bracket arm near its inner end. The shank of the hook 25 is longer than the shank of the hook 24, 5 so that the rod 23 may be parallel to the bracket arm. When in position on the bracket arm, the rod is above the same, in spaced relation therewith and with the shelf 17, so as to extend across the bedding lying 10 on the shelf. A holding rod is attached to each bracket arm, and the bedding is therefore securely held down on the shelf.

The device is simple in construction, and it can be easily and cheaply manufactured, 15 and readily applied to any building.

It will be understood, of course, that the device is not limited to the particular use stated, but may be employed for supporting other articles.

20 We claim:

1. A support comprising a horizontal arm and a downwardly and inwardly extending arm at the outer end thereof, the inner ends of the arms having alined pivots, one of 25 which pivots has a portion which is non-circular in cross-section, and bearings in which the pivots are slidably mounted, the bearing of the last-mentioned pivot conforming to the non-circular portion thereof, and 30 said last-mentioned pivot having a retaining part extending beneath its bearing.

2. A support comprising a horizontal arm and a downwardly and inwardly extending arm at the outer end thereof, the inner ends 35 of the arms having alined pivots, one of which pivots has a portion which is non-circular in cross-section, and bearings in which the pivots are slidably mounted, the bearing of the last-mentioned pivot con-

forming to the non-circular portion thereof, 40 and said last-mentioned pivot having a shoulder, its bearing having a top recess in which the shoulder is adapted to seat.

3. A support comprising a pair of laterally spaced bracket arms, attaching means 45 for said arms, an article-supporting shelf mounted on the bracket arms, article-holding members extending above the shelf and having depending hooks engageable with the bracket arms, and clips fastening the shelf 50 to the bracket arms.

4. A support comprising a pair of laterally spaced bracket arms, attaching means for said arms, an article-supporting shelf mounted on the bracket arms, and article-holding members extending above the shelf 55 and having depending hooks engageable with the bracket arms.

5. A support comprising a pair of laterally spaced bracket arms, attaching means 60 for said arms, an article-supporting shelf mounted on the bracket arms, and article-holding members extending above the shelf and having depending hooks engageable 65 with the bracket arms, the outer ends of the bracket arms having upstanding loops engageable by corresponding hooks of the holding members.

In testimony whereof we affix our signatures in the presence of two witnesses.

NORRIS C. COVINGTON.
